UNITED STATES PATENT OFFICE.

JAMES M. TRACKWELL, OF SKOOKUMCHUCK, WASHINGTON TERRITORY.

WOOD-BORING MACHINE.

SPECIFICATION forming part of Letters Patent No. 246,840, dated September 6, 1881.

Application filed June 13, 1881. (No model.)

To all whom it may concern:

Be it known that I, JAMES MASON TRACKWELL, of Skookumchuck, in the county of Lewis, Washington Territory, have invented 5 certain useful Improvements in Boring-Machines, of which the following is a specification.

My invention relates to an apparatus which is more particularly intended for boring in the 10 trunks of trees, either while standing or when fallen, but is applicable to various kinds of wood-boring.

The invention consists in a novel construction and combination, with an auger-stock and 15 its carrying-frame, of a frame and devices connected therewith for holding the auger in place while at work, as hereinafter particularly described.

In the accompanying drawings, Figure 1 represents 20 a front view of an apparatus embodying my improvements. Fig. 2 is a side view of the same. Fig. 3 is a horizontal section taken in the line $\alpha\alpha$ of Fig. 1.

Similar letters of reference indicate corresponding parts.

A represents a forked bar, having the lower 25 ends of the two branches sharp-pointed and their upper ends joined to form a head, a , to which is attached a cross-bar, B. The two branches are provided with ribs or guideways D for engagement with the carrying-frame C of an auger-stock operated by means of cranks e and bevel-gearing f. This frame and the guideways are similar to those heretofore in 30 common use for boring and mortising purposes. In such cases the guideways are provided with feet, which rest upon the work.

In my invention I attach the guideways to the forked bar A and dispense with the feet.

G represents a rod, having its lower end 40 pointed and provided with a cant-hook, g. The upper end of the rod is connected, by a sleeve, H, and set-screw J, with the lower end of a forked bar, K, the upper ends of which are provided with eyes l, and spring into place on 45 pivots i at the ends of the cross-bar, B.

In using this invention the points of the forks A are driven into the wood by a blow on the head a with a mallet, and the apparatus is held steadily in place by means of the hook g, 50 or the point at the lower end of the rod G, which rod may be adjusted to any desired angle by means of the sleeve H and set-screw J. The boring is then proceeded with in the usual manner. When the auger is to be raised the 55 vertical bevel-wheel f engages with an adjustable rack-bar, M, which is swung out of the way, as in the ordinary apparatus, while the boring is progressing.

Having thus described my invention, I claim 60 as new and desire to secure by Letters Patent—

In a boring-machine, the combination, with the auger-frame C, the bevel-gear wheels f, and the swinging rack-bar M, of the forked bar A, having its lower ends pointed and its upper 65 ends joined and formed into a head, and provided with the sides or guideways D, the cross-bar B, the forked bar K, provided with the sleeve H and set-screw J, and the pointed and hooked rod G, substantially as herein shown 70 and described.

JAMES MASON TRACKWELL.
